Attorney

UNITED STATES PATENT OFFICE.

BENJAMIN B. WALSTON, OF DALLAS, TEXAS.

DOOR HOLDER.

Application filed October 31, 1922. Serial No. 598,108.

To all whom it may concern:

Be it known that I, BENJAMIN B. WALSTON, a citizen of the United States, residing at Dallas, in the county of Dallas and State 5 of Texas, have invented certain new and useful Improvements in Door Holders, of which the following is a specification.

This invention relates to new and useful improvements in door holders.

10 The object of the invention is to provide a simple and efficient device of improved construction adapted to be mounted on a door and the casing thereof for holding the door open in various positions.

15 A construction designed to carry out the invention will be hereinafter described, together with other features of the invention.

20 The invention will be more readily understood from a reading of the following specification and by reference to the accompanying drawings, in which an example of the invention is shown and wherein:

25 Fig. 1 is a side elevation of a door provided with a device embodying the invention, portions of the door being broken away,

Fig. 2 is a cross-section of the door showing the device in plan,

30 Fig. 3 is a detail of the door in open position, and

Fig. 4 is an enlarged detail of the locking mechanism.

In the drawings the letter A designates a door and B the casing thereof. The device is 35 preferably mounted approximately on a line with the door knob 10 so as to be convenient for operation, and includes a hinge 11 secured to the casing B. The hinge has an elongated shank 12 pivotally connected to 40 which is an elongated latch bar 13. This bar is passed thru a guide 14 and between a pair of ears 15 adjacent the free end of the bar. An elongated narrow plate 16 underlies the bar 13 in a corresponding recess in 45 the door (Fig. 4). The outer end of the plate is provided with a plurality of alined apertures or sockets 17 for receiving a stud 18 on the outer end of the bar 13. The stud is normally held out of the sockets by a 50 spring 19 secured to the said bar and bearing against the plate 16. A latch operating lever 20 is pivoted between the ears 15 and has a head 21. The head is adapted to engage the bar 13 when the lever is swung 55 at right angles to the door, the adjacent

corner of the head being rounded so that it will easily ride over the said bar. A housing 22 is mounted over the sockets 17 and is adapted to receive the end of the latch bar when the door is swung.

60 In operation the door is opened to the desired position, the latch bar at the same time sliding into the housing 22. The lever 20 is then swung at right angles, the head 21 pressing the latch bar against the plate 65 16, whereby the stud 18 enters the nearest socket 17. It will be seen that both ends of the latch bar are thus locked, whereby the door A is prevented from swinging. When it is desired to close or otherwise 70 change the position of the door it is only necessary to swing the lever to a parallel position, whereby the spring displaces the latch bar and the same is permitted to slide freely.

75 Various changes in the size and shape of the different parts as well as modifications may be made within the scope of the appended claims.

80 What I claim, is:

1. The combination with a hinged door and a fixed support adjacent thereto, of a connection pivoted to the said support, a spring pressed latch bar pivoted to the connection, a plate secured to the door at the outer end of the said bar, said plate being provided with a plurality of sockets, means on the latch bar for engaging in said sockets, and means for engaging said latch bar holding said means in one of said sockets, whereby both ends of the said bar are locked and the door is held rigid.

85 2. The combination with a hinged door and a fixed support adjacent thereto, of a connection pivoted to the said support, a spring pressed latch bar pivoted to the connection, a plate secured to the door at the outer end of the said bar, said plate being provided with a plurality of sockets, means on the latch bar for engaging in said sockets, and a latch operating lever adapted to engage the outside of the said bar and hold the said means in one of the said sockets, whereby both ends of the said bar are locked and the door is held rigid.

95 3. The combination with a hinged door and a fixed support adjacent thereto, of a hinge member secured to said support and having a pivotal shank, an elongated latch bar having one end pivoted to the said 100 110

shank, a pair of pivotal ears mounted one on each side of the latch bar adjacent its free end, a plate mounted on the door at the free end of said bar and having a plurality of sockets, a stud carried by the latch bar for engaging in said sockets, and a lever pivotally mounted between said ears

and adapted to engage the latch bar and hold the said stud in one of the said sockets, whereby both ends of the said bar are locked and the door is held rigid.

In testimony whereof I affix my signature.

BENJAMAN B. WALSTON.
